UNITED STATES PATENT OFFICE.

WILLIAM H. BOTHWELL, OF PHILADELPHIA, PENNSYLVANIA.

DESIGN FOR A BOWING-CLASP FOR WINDOW-SHUTTERS.

SPECIFICATION forming part of Design No. 25,781, dated July 14, 1896.

Application filed May 28, 1896. Serial No. 593,510. Term of patent 7 years.

To all whom it may concern:

Be it known that I, WILLIAM H. BOTHWELL, a citizen of the United States, residing at the city of Philadelphia, in the county of Philadelphia and State of Pennsylvania, have invented and produced a new and original Design for Window-Shutter Bowing-Clasps, of which the following is a specification, reference being had to the accompanying drawings, forming part thereof, and in which—

Figure 1 is a side elevational view of a window bowing-clasp, illustrating my design; and Fig. 2 is a front view of the same, these two views being deemed necessary to fully illustrate my design.

The leading feature of my design consists of a window-shutter bowing-clasp having the two substantially parallel straight panels, both merging at one end in a circular or ring-shaped enlargement, and one of said panels terminating at the other end in a gooseneck-shaped enlargement projecting upward in a plane over the square-shaped end of the other panel.

Referring to the drawings, A and B are the

two straight panels arranged parallel with each other. These two panels terminate at one end in a ring-shaped enlargement D, the periphery of which extends above and below the upper and lower faces of respectively the upper panel A and the lower panel B. The opposite end E of the panel A is substantially square, while the corresponding end of the panel B terminates in a gooseneck-shaped enlargement F, projecting upward in a plane extending over the square-shaped end of the panel A.

Having thus described my invention, what I claim as new, and desire to secure by Letters Patent, is—

The design for a window-shutter bowing-clasp, substantially as shown and described.

In testimony whereof I have hereunto set my signature in the presence of two subscribing witnesses.

WILLIAM H. BOTHWELL.
